UNITED STATES PATENT OFFICE.

HARRY A. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

CIRCULAR-KNITTING MACHINE.

1,127,766.

Specification of Letters Patent.

Patented Feb. 9, 1915.

Application filed April 15, 1913. Serial No. 761,200.

To all whom it may concern:

Be it known that I, HARRY A. HOUSEMAN, a citizen of the United States, residing at Philadelphia, county of Philadelphia, and 5 State of Pennsylvania, have invented a new and useful Improvement in Circular-Knitting Machines, of which the following is a full, clear, and exact description, reference being had to the accompanying drawings, 10 which form a part of this specification.

In an application filed by me, jointly with Harold E. Houseman, of even date herewith, Serial No. 761,199, dated April 15, 1913, there is set forth a circular knitting machine 15 for the manufacture of hosiery, and especially that type of machine in which the needle cylinder rotates and the cam cylinder or cam ring remains stationary. This machine is adapted to successively knit the leg, 20 heel, foot and toe; but no means are set forth in said application to adapt it to the manufacture of half hose.

The object of the present invention is to adapt said machine to the manufacture of 25 half hose.

In the manufacture of half hose, after the toe is completed, it is necessary to knit a limited number of round-and-round courses, stop the machine, press the stocking off the 30 needles, withdraw the needles from operative engagement with the ordinary knitting cams and level all needles preparatory to the transferring operation, and then bring the needles again into operative relation with 35 the ordinary knitting cams to permit the resumption of circular knitting to knit the leg of another stocking.

In the present invention, means are provided to permit and effect this operation, 40 said means being in part novel *per se*, and in part such novel means combined with certain mechanism set forth in said application and with other mechanism set forth in Patent No. 1,078,679 issued to me November 45 18, 1913. This patent sets forth a machine, especially adapted to the manufacture of half-hose, which is a division of Patent No. 1,078,677, issued to me November 18, 1913, in which the needle cylinder is the stationary 50 element and the cam cylinder the rotary element. It will therefore be understood that while the present application sets forth only such part of a complete automatic circular knitting machine as is necessary to a full 55 understanding of the present invention, such

complete machine, with the present invention applied thereto, may be built by one skilled in the art by reference to the last-mentioned Patent No. 1,078,677 as modified by the first-mentioned application Serial No. 60 761,199; it being understood, however, that the present invention is not limited in its application to machines of the specific construction of those set forth in said application and patents. 65

In the drawings: Figure 1 is a front elevation of a part of the machine, illustrating principally the mechanism for rotating and oscillating the needle cylinder. Fig. 2 is a horizontal section on the line 2—2 of Fig. 1. 70 Fig. 3 is a detail sectional view showing the principal mechanism for shifting from rotation to oscillation and vice versa. Fig. 4 is a side elevation of the machine, partly broken away. Fig. 5 is a plan view of part of the 75 machine. Fig. 6 is a development showing in diagram the cams for respectively raising and lowering the rear bank of needles. Fig. 7 is a detail view, in plan, showing part of the needle cylinder and cam ring, the ordinary knitting cams and the means for moving the latter into position to permit leveling of all the needles. Fig. 8 is a front view of Fig. 7 with the knitting cam actuating lever omitted. Fig. 9 is a vertical section on the 80 line 9—9 of Fig. 7 with the knitting cam actuating lever omitted. Fig. 10 is a vertical section on the 85 line 9—9 of Fig. 7 with the knitting cam actuating lever omitted.

a is the frame of the machine and *b* the bed plate for the needle cylinder, cam ring and appurtenant mechanism. The needle 90 cylinder *e* has secured to its lower end the driven gear 11 (which is actuated as herein-after described), supported on the bed plate *b*.

The rotatable needle cylinder is provided 95 with radial slots extending inward from its outer wall, the needles *f*, *g*, extending within these slots and being movable upward therein to render them inactive, as is well understood in the art.

Supported on the top of the bed plate is the cam ring *h* which carries the ordinary knitting cams for actuating the needles.

As is well understood, during the knitting of the leg of the stocking, and during the knitting of that part of the stocking between the heel and toe (which I shall call the foot), the needle cylinder is continuously rotating and all the needles are moved down and in action. During the knitting of 110

the heel and toe, the needle cylinder is oscillated, and the needles *g* extending throughout one-half the circumference of the needle bed (hereinafter referred to as the rear bank 5 of needles) are initially thrown out of action. This is effected by providing the needles *g* with long butts and causing a cam *n* (hereinafter referred to) to be moved into position to engage all the long butt 10 needles and move them up in their slots. During the oscillation of the needle cylinder, the needles *f* extending throughout the remaining semi-circumference of the needle bed (that is, the front bank of needles) are 15 thrown out of action, one at a time, first at one end of the semi-circumference and then at the other end, and so on alternately until a limited number of needles in the central part of the semi-circumference are in action. 20 The needles are then thrown into action one at a time in the reverse order in which they are thrown out. This operation is effected by means of two sets of pickers whose construction and operation is set forth in said 25 application Serial No. 761,199 but which are not herein shown or described, as they form no part of the present invention.

The gear 11 on the knitting cylinder is driven from the gear 12 on the clutch shaft 30, on which are slidably mounted the two pinions 21 and 22, which have sleeves to which are yoked the vertically movable arms 24, 24, which are moved up or down in unison as hereinafter described. The clutch 23 35 is fixed on the shaft 20, between pinions 21 and 22. The upper pinion 21 is constantly rotated and the lower pinion 22 constantly oscillated. When the arms 24 are moved downward, thus engaging the rotary pinion with the clutch 23 and disengaging the oscillatory pinion 22 therefrom, the gear 12 is continuously rotated, thus rotating the needle cylinder 40 and the lower pinion 22. When the arms 24 are elevated, thus disengaging the rotary pinion 21 from the clutch 23 and engaging the oscillatory pinion therewith, the gear 12 is constantly oscillated, thus oscillating the knitting cylinder 45 and the arms 24. The pinion 21 is constantly rotated by means of a spur gear 25 meshing with the pinion 21. The shaft 26 of the spur gear 25 is also carries a bevel gear 27 driven from a bevel pinion 28 on the driving shaft 29. The pinion 22 is constantly oscillated by the following means. On the shaft 26 is a crank 29 connected by a link 30 with an arm 31 turning on a post 32. Extending from the hub of the arm 31 is a quadrant 33 engaging the pinion 22. The arms 24 are secured to a post 60, which has a pair of collars 61 between which extend the forked ends of a lever 62 pivoted between its ends on the frame of the machine. The lever 62 is actuated by means of a double cam 63, 64 secured to a sleeve 67 on

the shaft 69. These cams rotate together and may be integral one with another. Each cam has a high part and a low part. The high part of cam 63 is adapted to coact with an arm 65 on the lever 62. The high part 70 of cam 64 is adapted to coact with an arm 66 on the lever 62. When the high part of cam 63 coacts with the arm 65, the post-engaging end of the lever 62 is moved and held down, thereby moving down the post 75 60, the arms 24 and the pinions 21 and 22, thereby clutching pinion 21 with the clutch 23 and dictating the rotation of the needle cylinder. When the high part of cam 64 coacts with the arm 66, the post engaging end 80 of lever 62 is held up, thereby dictating the oscillation of the needle cylinder. The length of the high part of each of the cams 63 and 64 corresponds with the length of the low part of the other cam, and the arrangement is such that when the high part of one cam starts to ride under its corresponding lever arm, the high part of the other cam starts to recede from its corresponding lever arm. Thus the lever 62 is 85 always in positive engagement with one cam or the other.

The double cam 63, 64, is caused to turn by means of a pattern ratchet wheel 68, also secured to the sleeve 67, which ratchet wheel 95 is turned initially by first turning the sleeve 67 and then by means of a pawl 70. In Patent No. 1,076,679 hereinbefore referred to is fully set forth pattern mechanism for initially turning the sleeve 67. 100 This mechanism is capable of application to the present machine and need not therefore be described. It is sufficient to say that just before it is desired to change from rotation to oscillation, the cam shaft 77 (which is geared to the sleeve 67 by means of the intermeshing pinions 18 and 19) is given a partial turn, thereby turning the sleeve 67 105 and the ratchet wheel 68. It is to be noted that the pawl 70 is constantly reciprocated by means to be hereinafter described. The ratchet wheel 68 has a number of teeth, all of uniform length except one 80, which is substantially longer than the others. During oscillation of the cam cylinder, the pawl 70 plays upon the long tooth, its extent of movement being insufficient to cause it to drop back of the same. Consequently, it is 110 inoperative to turn the ratchet wheel 68. But after the ratchet wheel has been given the initial turn just described, the long tooth is advanced to such position that on the next reciprocation of the pawl 70 it drops back of the long tooth 80 and proceeds to turn the ratchet wheel together with the double cam 63, 64. 115 As the pawl 70 engages and pushes the next tooth of the ratchet 68, the high part of cam 63 recedes from the lever arm 65 and 120 125 130

the high part of cam 64 engages lever arm 86, thereby lifting the post-engaging end of lever 62, clutching the lower or oscillatory pinion 87 to the clutch shaft 20 and unclutching the rotary pinion 21, and causing the needle cylinder to oscillate.

The constant reciprocation of the pawl 70 is effected by securing to the hub of lever 31 a section of a bevel pinion 81 which drives a similar pinion 82 on the shaft 69. To this shaft is secured a holder 83 carrying the pawl 70.

At the same time the machine is shifted from rotation to oscillation, it is necessary to clear out of action the rear bank of needles *g*. This is effected by means of a cam *n* on a rock-shaft 121 carrying an arm 120 in line of travel of a cam *m* on a rotatable ratchet ring *i* arranged concentric with the needle cylinder and supported on the bed plate *b*. This mechanism is more specifically set forth in said application Serial No. 761,199, as is also the means for actuating the ratchet ring *i* coördinately with the shift from rotation to reciprocation and vice versa, which actuating means is not herein shown, as it forms no part of the present invention.

At the same time are moved into operative position the pickers, not herein shown, for moving out of action, one at a time, needles at one end of the front bank of needles *f*, and for moving out of action, one at a time, the needles at the other end of the front bank of needles. In said application Serial No. 761,199 I have also shown means, controlled by the cam ring *i*, for rendering pawl 70 inoperative to turn the ratchet wheel 68, pickers for effecting the reinstatement into operative position, one at a time, of the needles *f*, previously rendered inoperative, in approximately the reverse order in which they were previously thrown out, and means, controlled by the ratchet ring *i*, for controlling their operation. Such means are fully set forth in said application Serial No. 761,199, but are not herein set forth, as they form no part of the present invention. It is sufficient to say that, as before described, after the pawl 70 turns the ratchet wheel 68 to cause the shift from rotation to oscillation and the ratchet wheel *i* is turned to cause the cam *m* to move the cam *n* into position to raise out of operative position the rear bank of needles *g*, the following operations occur: The needles *f* are raised by one set of pickers, out of operative position, one at a time, thus gradually narrowing the fabric; the pawl 70 is rendered inoperative to turn the ratchet wheel 68, the needles *f*, previously rendered inoperative, are lowered by another set of pickers, into operative position, one at a time, thus gradually widening the fabric; the pawl 70 is again rendered operative to turn the ratchet

wheel, the machine is shifted from oscillation to rotation, a cam *r* on the ratchet ring *i* causes a needle-depressing cam *s* to move down into operative position the needles *g* of the rear bank, and all the pickers are rendered inoperative; thus again putting the machine into condition for rotary work.

The needle-depressing cam *s* is herein shown diagrammatically, and reference may be had to said application Serial No. 761,199 for a full understanding of its specific construction and operation and the means for operating it from the ratchet ring *i*, it being understood that the specific structure of neither the mechanism for raising, nor the mechanism for lowering, the rear-bank of needles *g* is of materiality or importance in connection with the present invention.

The above described series of operations occurs during the knitting of both heel and toe. After the toe is completed, it is necessary to stop the machine, as hereinbefore described. I have adapted the stop mechanism set forth in the hereinbefore mentioned Patents No. 1,078,677 and No. 1,078,679 to the present machine. Such mechanism comprises a spring-actuated belt-shifter, and means for controlling its operation. I have not herein shown the belt shifter contrivance, as the same is not necessary to be disclosed in order to fully understand the present invention, and any appropriate stop-contrivance may be employed; but I have herein shown the mechanism for controlling the stop-contrivance, as the same is directly connected with the ordinary knitting cams, which connections are peculiar to the present invention. Such control mechanism will now be described.

The stop contrivance is controlled from a lever 160, which in turn is actuated by a cam-wheel 161. This cam-wheel is on a shaft 162, which also carries the ratchet wheel 163. On the main driving shaft *t* is a spur gear 166, meshing with a spur gear 167. A link 168 connects a crank pin on gear 167 with the outer end of the arm 165 at which point is carried a pawl 170. The arm 165 is loosely pivoted on shaft 162. The pawl 170 engages the teeth of the ratchet wheel 163. These teeth extend all the way around the periphery of the wheel 163 except for a blank space somewhat shorter in length than the space occupied by three teeth. Mechanism is provided (as hereinafter described) whereby after the knitting of the toe is completed, the ratchet wheel 163 is turned to bring the first tooth of the wheel into operative relation with the pawl. Thereafter the ratchet wheel 163 will be turned a distance of one tooth at each revolution of the driving shaft. After the ratchet wheel 163 is turned any predetermined number of teeth, the cam wheel 161 actuates the lever 160 which in turn actu-

ates the stop-contrivance, thereby stopping the machine. After the machine is re-started, the ratchet wheel 163 continues to turn until the pawl 170 has actuated the last 5 tooth, when it proceeds to play idly on the untoothed portion of the periphery of the wheel.

The ratchet wheel 163 is subsequently turned to bring the pawl 170 again into operative relation with the ratchet wheel by the following means: On the shaft 77 is a cam wheel 171. A bell-crank lever 172 is pivoted on the machine frame, one arm of the lever being held in contact with the cam 15 face of the wheel 171 by a spring 173 and the other arm of the lever being connected to the upper end of a link 174, the lower end of this link having a pin and slot connection with the intermediate part of the lever 175. 20 This lever is pivoted at one end on the machine frame and at the other end has a projection in line of travel of a lug 176 on the ratchet wheel 163. On the link 174 is a fixed pawl 177 adapted to engage the ratchet 25 wheel 163. A spring 178, extending between projections on the lever 175 and link 174, maintains the pawl 177 in engagement with the teeth of the wheel 163. Just before the first shift from oscillation to rotation 30 (which occurs in passing from heel to the foot) the cam wheel 171 (which is provided with two high points, the second being higher than the first) engages the lever 172. As the lever 172 rides upon the first high 35 point of the cam wheel 171, the link 174 is depressed. In shifting from oscillation to rotation, the cam wheel 171 is turned still farther and the lever 172 rides over the highest point of the cam. The ratchet 40 wheel 163 is thus turned by the pawl 177 but not a sufficient distance to bring the pawl 170 into operative relation with the first tooth of the ratchet wheel.

During the knitting of the foot and toe 45 the parts described remain in inoperative position, but on the shift from oscillation to rotation at the beginning of circular knitting, the cam wheel 171 again acts upon the lever 172 and link 174 as before described, 50 and at this time the ratchet wheel 163 is advanced a sufficient distance to bring the pawl 170 into operative relation with the ratchet wheel 163, whereupon the operation of the latter proceeds as before described until the 55 machine is stopped.

After the machine is stopped, all the needles are in operative position, that is, in the 60 position they occupy in the knitting of circular fabric. The yarn is broken by hand, and the stocking is pressed off the needles by turning the machine about two revolutions. During this action all the needles are 65 acted upon by the ordinary knitting cams *p* and, save for the needles that are at any given time in actual engagement with the

knitting cams, all the needles are on the same level. It is necessary, however, to bring all the needles on the same level and to effect this end the following means are provided to disengage the ordinary knitting cams *p* 70 from the needles. As is shown in Figs. 7, 8 and 9, these cams are mounted on a radially movable slide or carrier 200, which is sleeved loosely on a pin 201, which is threaded in the cam ring *h*. A coil spring 202, surrounding the pin 201 and confined between the head of the pin and the slide 200, normally holds the slide 200 in its innermost position, so that the cams *p* are in position to engage both the short butts of the needles *f* of the 80 front bank and the long butts of the needles *g* of the rear bank.

It will be understood that if, after the fabric is pressed off the needles as before described and while the knitting cams *p* are 85 in engagement with the long butt needles *g*, the slide 200 be moved out, as shown in Fig. 9, far enough to enable the cams to entirely clear the short butts of the needles *f*, and then if the machine is turned by hand until 90 all the long butt needles *g* pass beyond the knitting cams onto a common level, such of the short butt needles *f* as have by this time moved opposite the knitting cams will not have been engaged thereby but will have 95 remained on the level to which they have been previously brought, and consequently all the needles *f* and *g* will be on the same level. This movement of the cam slide is effected automatically at the proper time 100 by the following mechanism.

The cam slide 200 is shaped to engage the forked end of a lever 203 pivoted between its ends on the main frame (see Figs. 4 and 5). The other end of this lever is pivotally 105 attached to one arm of a bell crank lever 204, also pivoted on the main frame. The other arm of the bell crank lever is pivotally attached to a rod 205, the other end of which is pivotally attached to the arm 208, the end 110 206 of which is in line of movement of a cam 207 on the shaft 162.

The cam 207 is so positioned on the shaft 162 that, after the machine is stopped, the cam 207 will operate the rod 205 on the third 115 subsequent rotation. This allows the machine to be turned twice, as before described, to permit the fabric to be pressed off the needles, and then on the next turn, and while the knitting cams *p* are engaging cer- 120 tain of the long butt needles, the knitting cams, by means of the connections above described, are drawn out into the position shown in Fig. 9. The machine, on this rotation is turned far enough to cause all the 125 long butt needles to clear the knitting cams, but not far enough to bring any of the long butt needles again back to the cams. All the needles are thus brought onto a common level. The transferring operation then 130

proceeds, this operation, however, having nothing to do with my invention.

After the transferring operation the machine is given a couple of turns by hand to reengage the thread with the needles. After the needle cylinder turns part of a revolution to bring the long butt needles *g* in engagement with the cams *p*, the cam 207 recedes from the end 206 of arm 208 and the spring 202 at once moves the cam slide 200 inward to its normal operative position. After the cam slide 200 thus moves into its inward position, less than a complete turn of the needle cylinder operatively engages the cams *p* with all the short butt needles. Thereafter the cams operate alike on both banks of needles, the machine operating thereafter to continue rotary work and form the leg or ankle of the stocking until the shift to oscillation preparatory to knitting the heel.

The knitting cams on a machine of the character of that herein set forth are subject to unequal wear due to the fact that on rotary work the cam which acts as the stitch-forming cam receives the greater wear. In order that, notwithstanding this fact, the cams on both sides may be maintained on the same level, I cause the cam slide to rest upon two screws 210 engaging the cam ring, both of which are adjustable to vary the level of the corresponding end of the cam slide.

Having now fully described my invention, what I claim and desire to protect by Letters Patent is:

1. In a circular knitting machine, in combination, the needle cylinder, the driving shaft, two sets of needles in the needle cylinder, knitting cams normally in operative relation with both sets of needles, means adapted to render the cams inoperative to actuate one set of needles, thereby permitting all the needles of the other set to pass through the cams in the turning of the needle cylinder and thus effect the leveling of all the needles of both sets, means to stop the machine, connections from the driving shaft to the stop means and the cam actuating means to first effect the operation of said stop means and next, in the subsequent manual turning of the driving shaft, to effect the operation of said cam actuating means; control means, and mechanism actuated thereby to render said connections operative, whereby the machine will be stopped at the proper time to permit the subsequent leveling of all the needles preparatory to the transferring operation.

2. In a circular knitting machine, in combination, the needle cylinder, the driving shaft, two sets of needles in the needle cylinder, one set having relatively short butts and the other set having relatively long butts, a cam adapted to engage the long butt needles and move them out of opera-

tive position, a cam adapted to engage the long butt needles and return them to operative position, knitting cams normally in operative relation with both sets of needles while the long butt needles are in operative position, means adapted to move the knitting cams, while the long butt needles are in operative position, out of operative relation with the short butt needles while maintaining them operative with the long butt needles, thereby permitting all the short butt needles to pass through the cams in the turning of the needle cylinder and thus effect the leveling of all the needles, means to stop the machine, connections from the driving shaft to the stop means and the knitting cam moving means to effect their operation, control means and mechanism actuated thereby to render said connections operative, whereby the machine will be stopped at the proper time to permit the leveling of all the needles preparatory to the transferring operation.

3. In a circular knitting machine, in combination, a rotatable needle cylinder, a relatively stationary cam ring, the driving shaft, rotary driving means and oscillatory driving means connected with and operable from the driving shaft, shifting mechanism for alternately connecting the two driving means with the needle cylinder, pattern controlled means governing the operation of the shifting mechanism, pawl and ratchet mechanism, control means to place the pawl and ratchet mechanism in driving relation with the driving shaft, knitting cams, means and mechanism actuated thereby controlled by the pawl and ratchet mechanism to stop the machine, and means operable by the pawl and ratchet mechanism adapted to render the knitting cams inoperative to actuate certain needles while maintaining their operative relation with other needles, thereby permitting the pawl and ratchet mechanism to effect the stoppage of the machine and permit the leveling of the needles at a stage in the operation dictated by said control means.

4. In a circular knitting machine, the combination with the needle cylinder, the cam ring, the driving shaft, and pattern controlled means governing the rotation of the needle cylinder, of pawl and ratchet mechanism, means actuated by said pattern controlled means to place the pawl and ratchet mechanism in driven relation with the driving shaft, two sets of needles in the needle cylinder, one set having relatively short butts and the other set having relatively long butts, knitting cams, a slide, carrying the cams, movable radially on the cam ring, said cams being adapted in one position to engage the butts of all the needles and in another position to clear the short butt needles, a lever connected with and adapt-

- ed to move the slide into the last-named position, a spring normally holding the slide in the first-named position, a bell-crank connected with and adapted to operate said lever, a rod connected with and adapted to operate the bell crank, and a cam carried by the pawl and ratchet mechanism and adapted to operate said rod.
5. In a circular knitting machine, the combination with the needle cylinder and two sets of needles therein, one set having relatively short butts and the other set having relatively long butts, of a cam ring, a radially disposed pin thereon, a slide 10 loosely mounted on the pin, a spring between the head of the pin and the slide tending to hold the latter in its inner position, knitting cams on the slide in alignment with the butts of all the needles when the slide is 15 in said position, and an actuating lever, connected with the slide, adapted to move the slide out, against the action of said spring, to cause the knitting cams to clear the short butt needles.
6. In a circular knitting machine, the combination with the needle cylinder and cam ring, of the knitting cams, a carrier therefor supported on the cam ring, and means between the carrier and the cam ring 20 to adjust one end of the carrier relatively to the other end to compensate for wear.
7. In a circular knitting machine, the combination with the needle cylinder and cam ring, of the knitting cams, a carrier therefor, and means between the carrier and the cam ring to support the carrier from the
- cam ring, said means being adjustable to permit the vertical adjustment of one end of the carrier relatively to the other.
8. In a circular knitting machine, the combination with the needle cylinder and cam ring, of the knitting cams, a carrier therefor, two supports for the knitting cam carrier between the cam ring and the carrier at opposite ends of the latter, said supports 40 being vertically adjustable relatively one to the other.
9. In a circular knitting machine, the combination with the needle cylinder and cam ring, of the knitting cams, a slide radially movable on the cam ring and carrying the knitting cams, and supports for opposite ends of the slide, said supports being secured to the cam ring and vertically adjustable thereon relatively one to the other. 45
10. In a circular knitting machine, the combination with the needle cylinder, and cam ring, of the knitting cams, a radially movable slide carrying the knitting cams, a radially disposed pin on which the slide is 50 loosely sleeved, and screws on opposite sides of the pin, said screws being threaded in the cam ring and supporting opposite end portions of the cam-carrying slide. 55

In testimony of which invention, I have hereunto set my hand, at Phila. Pa., on this 3rd day of April, 1913.

HARRY A. HOUSEMAN.
